Primary Examiner — Kimberly Barnes*Assistant Examiner* — Alexandria Dubus(74) *Attorney, Agent, or Firm* — Kunzler Bean & Adamson, PC; Kaitlyn Haven(57) **CLAIM**

The ornamental design for a charging adapter storage bag as shown and described.

DESCRIPTION

FIG. 1 is a front, right and top perspective view of a charging adapter storage bag in an open position, showing my design. FIG. 2 is a rear, left and bottom perspective view thereof. FIG. 3 is a front elevation view thereof. FIG. 4 is a rear elevation view thereof. FIG. 5 is a left side elevation view thereof. FIG. 6 is a right side elevation view thereof. FIG. 7 is a top plan view thereof. FIG. 8 is a bottom plan view thereof. FIG. 9 is another front, right and top perspective view of the charging adapter storage bag in a closed position; and, FIG. 10 is another rear, left and bottom perspective view of FIG. 9. The dashed broken lines depict portions of the charging adapter storage bag that form no part of the claimed design.
